Primary Examiner—Terry A. Wallace
Attorney, Agent, or Firm—Roger A. Marrs[57] **CLAIM**

The ornamental design for bottle holder, as shown and described.

DESCRIPTION

FIG. 1 is a perspective view of a bottle holder showing my new design;

FIG. 2 is a side elevational view thereof with the opposite side being a mirror image thereof;

FIG. 3 is a top plan view thereof;

FIG. 4 is a bottom view thereof;

FIG. 5 is a front elevational view thereof; and,

FIG. 6 is a rear elevational view thereof.

The broken line showing of the bottle is for illustrative purposes only and forms no part of the claimed design.
